UNITED STATES PATENT OFFICE.

WILLIAM MARSHALL, OF DETROIT, MICHIGAN, ASSIGNOR TO BRIGGS MANUFACTURING COMPANY, OF DETROIT, MICHIGAN, A CORPORATION OF MICHIGAN.

FINISH-STRIP ASSEMBLY.

Application filed June 28, 1926. Serial No. 119,178.

This invention relates generally to finish strips for vehicle bodies and consists of certain novel features of construction, combinations and arrangements of parts as will be more fully described and particularly pointed out in the appended claims.

In the accompanying drawings:

Figure 1 is a side elevation of a door with a finish strip embodying my invention applied thereto.

Figure 2 is a cross sectional view taken on the line 2—2 of Figure 1.

Figure 3 is a cross sectional view taken on the line 3—3 of Figure 1.

Figure 4 is a detail perspective view of the finish strip, which is applied to the pillars.

Figure 5 is a detail perspective view of the header finish strip.

Figure 6 is a cross sectional view through a slightly modified form of construction.

Figure 7 is a cross section view through another modified form of construction.

Referring now to the drawings, 1 is a door of the vehicle body having the upright pillars 2 and the intermediate cross bar or header 3. As shown, the pillars 2 are preferably channel-shape and are provided with the lateral flanges 4 while the cross bar 3

is also preferably channel-shape and is provided with an upstanding flange 5. Overlapping these pillars and cross bar is a sheet metal panel 6 that constitutes the exterior

finish of the door. As shown, this panel 6

is secured at its edges to the flanges 4 and 5 and is provided between the pillars with a suitable window opening 7. To provide a

neat appearance, the panel 6 is provided at the upper and side edges of the opening 7

with the inwardly extending lateral flanges 8 and 9 respectively that have L-shaped rabbet portions 10 and 11 secured to the pillars and header. Thus the panel 6 and flanges

8 and 9 close the channels of the pillars and header and cooperate therewith to form box-like frame members.

Heretofore it has been a practice by some body manufacturers to secure strips of molding to the side walls of the pillars to receive

the window glass runs and to secure separate strips or panels of fabric trimming material to the inner walls of the pillars and

header to provide a neat finish for the interior of the vehicle body. With such constructions, considerable time and labor has been required to form the separate parts referred to and to secure the same by separate assembly operations to the pillars and header. In the present instance however this is accomplished in a single operation by providing metal finish strips 12 and 13 respectively that not only carry the fabric trimming material but also hold it in position on the pillars and header. As shown, each strip 12 is preferably channel-shape and has the lateral flanges 14 and 15 respectively. Preferably the lateral flange 14 is return-bent inwardly toward the base 16 of the channel and is spaced slightly from the inner side wall 17 of the strip 12, while the flange 15 projects outwardly from the side wall 17 and overlaps the inner wall 18 of the pillar. As shown this flange 15 is substantially equal in width to the inner wall 18 of the pillar and curves inwardly toward the same so as to hold suitable trimming material, as will be herein-after described. Any suitable means such as the screws 19 may be used to secure the strips 12 to the pillars. As shown, these screws 19 extend through aligned openings 20 and 21 respectively in the outer and inner walls of the strips 12 and engage suitable nuts 22 anchored within the pillars.

The body portion 23 of the finish strip 13 preferably corresponds to the header finish strip shown in United States Patent No. 1,487,748, dated March 25, 1924, however the flange 24 of the body portion is preferably provided with an open return-bent portion 25 that has a lateral flange 26 overlapping the inner wall 27 of the cross bar 3. As shown, the outer side 28 of the return-bent portion 25 is substantially equal in width to the flange 24, while the lateral flange 26 is substantially equal in width to the inner wall 27 of the cross bar 3. Any suitable means such as the screws 29 may be used to secure the strip 13 to the header cross bar. As shown these screws are received in suitable openings in the body portion 23 and extend between the return-bent portion 25 and the channel portion 30 into suitable nuts 31 anchored in the cross bar 3.

In use, the strips 12 are secured to the side walls of the pillars so that the bases 16 of the strips are spaced slightly from the transversely extending walls 32 of the rabbets 10 and the strip 13 is secured to the lower wall of the cross bar 3 so that the channel portion 30 abuts the upright wall 33 of the rabbet 11. Any suitable channel-shaped strips 34 and 35 respectively may be secured in the rabbets 10 and 11 to receive the edges of a suitable window panel 36. To provide a neat interior finish I have provided strips 37 of fabric trimming material that conceal the lateral flanges 15 of the strips 12 and have marginal attaching portions 38 and 39 respectively. As shown the marginal portions 38 are folded around the free edges of the flanges 15 and are held thereby against the inner walls 18 of the pillars while the marginal portions 39 are received between the return-bent flanges 14 and the inner walls 17 of the channel strips 12. If desired suitable glue, etc., may be used to secure the trimming material 37 to the flange 15. Likewise a strip 40 of fabric trimming material is used to conceal the lateral flange 26 of the strip 13 and is provided with the marginal attaching portions 41 and 42 respectively. As shown, the marginal portion 41 is folded around the free edges of the flange 26 and is held thereby against the inner wall 27 of the cross bar 3, while the marginal portion 42 is received in the return-bent portion 25. Any suitable means such as glue may be used to secure the trimming material 40 to the flange 26 and in the return-bent portion 25.

In Figures 5 and 6 I have shown slightly modified constructions in which wooden pillars 50 and a wooden header 51 have been substituted for the metal pillars 2 and header cross bar 3. As shown, the strips 53 and 54 respectively are identical in construction to the strips 12 and 13 and the manner of attaching the fabric trimming material is the same as that shown in Figures 1 to 4 inclusive. With these constructions the screws 55 and 56 respectively engage directly with the wood pillars and header to secure the strips in place.

While it is believed that from the foregoing description, the nature and advantage of my invention will be readily apparent, I desire to have it understood that I do not limit myself to what is herein shown and described and that such changes may be resorted to when desired as fall within the scope of what is claimed.

What I claim as my invention is:

60 1. A finish strip assembly comprising a finish strip having a channel-shaped portion, and a flange projecting laterally outwardly from an edge of said channel-shaped portion and disposed at substantially right angles to one side wall of said channel-

shaped portion, and trimming material overlapping said flange and having a marginal portion secured in said channel-shaped portion.

2. A finish strip assembly comprising a 70 finish strip having a channel shaped portion provided with a flange extending laterally from one side thereof and having an open return bent portion extending from the other side and terminating within the channel, and trimming material overlapping said flange and having a marginal portion secured in said channel shaped portion between one wall thereof and the return bent portion of the other wall.

3. The combination with a frame member having a rabbet extending longitudinally of one side thereof, of a channel shaped finish strip cooperating with the rabbet to form a channel for a glass run and provided with a flange projecting laterally from one side thereof and an open return bent portion extending from the other side and terminating within the channel of the finish strip, trimming material overlapping said flange 90 and having a marginal portion extending within the channel of the finish strip between one wall thereof and the return bent portion, and headed elements for securing the finish strip to the said frame member and for clamping the marginal portion of said trimming material within the channel thereof.

4. The combination with a frame member having a rabbet portion extending longitudinally of one side thereof, of a channel shaped finish strip secured to said side and having its base portion cooperating with said rabbet portion to form a channel for a glass run, a lateral flange extending from one side of said finish strip and overlapping another side of said frame member, the other side of said finish strip being provided with an open return bent portion extending within the channel, and trimming material 105 overlapping said flange and having a marginal portion secured in said channel between the said return bent portion and one wall of the finish strip.

5. The combination with a frame member, 115 of a finish strip having a hollow body portion secured to one side of said frame member, and having a flange projecting laterally from said body portion and overlapping another side of said frame member, and 120 trimming material overlapping said flange and having one marginal portion thereof secured in said body portion.

6. The combination with a frame member, 125 of a finish strip having a hollow body portion secured to one side of said frame member and having a flange projecting laterally from said body portion and overlapping another side of said frame member, and trimming material having portions respectively 130

secured to said body portion, overlapping said flange, and extending between said flange and frame member.

7. The combination with a frame member, of a finish strip having a hollow body portion secured to one side of said frame member and having a flange projecting laterally from said body portion and overlapping another side of said frame member, and trimming material having portions respectively disposed within said body portion, overlapping said flange, and extending between said flange and last mentioned side of said frame member. 10

In testimony whereof I affix my signature.

WILLIAM MARSHALL.
